AUTOMATIC STARTING DEVICE FOR INTERNAL COMBUSTION ENGINES

Edwin L. McKinney and Harold E. Eagle, Victor-
ville, Calif., assignors of one-fifth to Charles
Wondra and M. C. Fitzgerald, both of Victor-
ville, Calif.

Application January 18, 1933, Serial No. 652,378

4 Claims. (Cl. 123—179)

This invention relates to starting devices for internal combustion engines and consists in the provision of means for automatically closing the circuit to the starting motor usually provided in automobiles as a part of a starting mechanism for the internal combustion engine, so that, if for any reason the internal combustion engine stops the device will cause the internal combustion engine to resume operation without requiring the attention of the operator.

Further the invention comprehends the provision of means whereby suction or vacuum created in the intake manifold of the internal combustion engine during operation thereof may be utilized for maintaining the device embodying the features of the present invention in a normally inactive position so as not to interfere with normal operation of the internal combustion engine.

20 The invention together with its numerous objects and advantages will be best understood from a study of the following description, taken in connection with the accompanying drawings wherein:

25 Figure 1 is a side elevational view of a portion of an automobile showing the invention applied thereto.

Figure 2 is a sectional elevational view of a device embodying the features of the present invention.

30 Figure 3 is a fragmentary longitudinal sectional view through a switch casing, the switch being shown closed.

35 Figure 4 is a longitudinal sectional elevational view through a switch actuating device forming part of the invention.

Figure 5 is a fragmentary elevational view of the switch casing.

40 Figure 6 is a top plan view of the cylinder forming part of the switch actuating device.

Figure 7 is a longitudinal sectional view through the cylinder.

Figure 8 is a plan view of a slide member.

45 Figure 9 is a sectional elevational view through one end of the slide member.

Figure 10 is a top plan view of a cylinder cap.

Figure 11 is a perspective view of a switch blade.

50 Figure 12 is a perspective view of a cam equipped shaft to be hereinafter more fully referred to.

Figure 13 is a perspective view of a stem attachment to be hereinafter more fully referred 55 to.

Figure 14 is a perspective view of a stop collar and

Figure 15 is an end elevational view of the piston and its stem.

Referring to the drawings in detail by reference numerals and reference being had to Figure 1 it will be seen that the invention may readily be applied to a conventional type of automobile and in the present instance there is shown a portion of such an automobile, the same including among other parts the internal combustion engine 1, hood 2, starting motor 3, accelerator pedal 4, and instrument board 5.

In its preferred embodiment the invention 15 consists of a switch casing 6 receiving in its upper end the enlarged end portion 7 of a cylinder 8 forming part of what may be termed a switch actuator. The end 7 of the cylinder is secured within the casing 6 through the medium of any suitable fastening element 9.

20 Arranged within the casing 6 is a switch that includes a pair of binding posts 10, 11 suitably mounted in a block 12 of insulating material arranged in the lower portion of the casing. The posts 10, 11 are connected in the circuit with the battery and the starting motor 3 through the medium of the wires 13. The post 10 is provided with a fixed contact 14 with which is co-operable a metallic spring like movable contact or blade 15 that is suitably anchored at one end 25 to the post 11. The blade 15 is normally flattened so as to tend to normally engage the contact 14 for closing the switch, and consequently the circuit to the starting motor.

25 The aforementioned switch actuating device 30 includes in addition to the cylinder 8 a piston 16 arranged to reciprocate within the cylinder and provided with a stem 17 having a threaded free end 18 on to which is screwed the socketed head 19 of a pin or stem extension 20. A lock 40 nut 21 is provided for securing the socket 19 at the desired adjustment on the end 18 of the stem 17. The free end of the pin 20 extends through a slot 22 provided in a curved portion of the switch blade 15, and is equipped with 45 laterally extending pins 23 engaging the blade 15 in a manner clearly shown in Figure 2. For the top or upper end of the cylinder 8 there is provided a cap 24 screwed on to said cylinder and this cap is provided with a threaded nipple 25 that extends through the top of the cap and is provided with a bore of relatively small diameter. A vacuum tube 26 has one end engaged with the nipple 25 and a relatively opposite end tapped into the intake manifold 27 of

the internal combustion engine 1 as suggested in Figure 1.

From the description of the invention thus far it will be seen that normally, under action of the switch blade 15 piston 16 is normally urged downwardly. When the internal combustion engine 1 is running the vacuum created in the intake manifold 27 will act on the piston 16 for drawing the same upwardly to the position shown in Figure 4 thus raising the switch blade 15 out of engagement with the contact 14. If, now for any reason, the internal combustion engine should stop, thus releasing vacuum in the intake manifold, piston 16 under action of the switch blade 15 assisted by gravity, will move downwardly so that the switch blade 15 will engage the contact 14 thus completing the circuit to the starting motor 3 causing the internal combustion engine to resume operation as is obvious.

20 A stop collar 28 of any suitable resilient material is seated within an annular groove 29 provided internally of the cylinder 8 at the upper end thereof and as shown in Figure 4 the upper end of the piston 16 abuts the collar 28 when the piston is at the limit of its upward movement thus serving to provide a suitable space in the upper end of the cylinder above the piston to insure efficient operation of the device. The cap 24 is also provided with a suitable aperture 30 in the top thereof for lubricating purposes, and a plug 30 normally closes the aperture.

Means is also provided for manually opening the switch arranged in the casing 6, and in the present instance such means comprises a shaft 31 extending transversely in the casing 6 and provided on an intermediate portion thereof with a cam 32 arranged to engage the switch blade 15 for swinging the blade upwardly to open the switch upon rotation of the shaft 31 for swinging the cam 32 from the full line position shown in Figure 1 to the dotted line position shown in said figure. On one end shaft 31 is provided with a crank arm 33 to which is connected one end of a Bowden wire 34 that leads upwardly through the instrument board 5 and is equipped with an actuating knob 36 so that the operator by suitably manipulating the knob 36 may rock the shaft 31 for opening or closing the switch as may be found desirable or necessary.

50 Means is also provided for holding the piston or plunger 16 in its upper or switch opening position; and such means in the present instance comprises an elongated slide 37 provided at one end with a relatively wide notch 38 merging into a relatively narrow notch 39. At its other end the slide 37 is provided with a slot 40 in which is adjustably secured through the medium of block nuts 41 an eye bolt 42.

The slide 37 is constrained to shift in a slot 43 provided in the enlarged end 7 of cylinder 8 as shown in Figure 4. The plunger or piston stem 17 adjacent its threaded end is reduced to accommodate the slotted portion of the slide 37 and to provide upper and lower stop shoulders 44, 45 to abut the slide 37 for limiting vertical movement of the piston.

70 The slide 37 is operatively connected with the throttle or accelerator pedal 4 through the medium of an arm 46 connected with the throttle valve operating rod 47 and a link 48 connecting the arm 46 with the eye bolt 42 all in the manner clearly suggested in Figure 1.

As is well known, when the speed of the internal combustion engine is relatively high, vacuum is reduced with the result that the plunger 16

would be free to move downwardly for closing the switch within the casing 6. However through the medium of the device just described, when the accelerator pedal 4 is pressed in for increasing the supply of fuel to the internal combustion engine, slide 37 will be moved to the position shown in Figure 4. With the slide in the position shown in said figure, it is apparent, that should the vacuum in the cylinder be released to the extent of permitting piston 16 to move downwardly, shoulder 44 thereof will engage the slide 37 at opposite sides of the slot 39 and the downward movement of the piston is thus limited to an extent sufficient to prevent movement of the switch blade 15 into engagement with the contact 14. When however the internal combustion engine is idle, or is running at a relatively low speed, slide 37 will be positioned for placing the slot 38 thereof relative to the stem 17 to permit the stem to move vertically through the slot to either a switch closing or opening position.

In operation, and when it is desired to use the device, the internal combustion engine is started in the usual manner and as vacuum develops in the line 26 piston 16 moves upwardly 25 for holding the switch blade 15 out of engagement with the contact 14. If for any reason the engine stalls relieving vacuum in the cylinder 8 the piston 16 moves downwardly and the switch blade 15 will move into engagement with the contact 14 for closing the circuit to the starting motor 3 resulting as is obvious in a resumption of operation of the internal combustion engine. Should the speed of the internal combustion engine become so excessive as to relieve vacuum in 35 the line 26 a closing of the switch will be prevented by reason of the fact, as before stated that as the accelerator 4 is moved downwardly for increasing the speed of the internal combustion the slide 37 is shifted to the position 40 shown in Figure 4 so as to limit downward movement of the piston 16.

When it is desired not to use the device the operator by pulling outwardly on the button 36 will rock the shaft 31 for swinging the cam 32 to the full line position shown in Figure 2 to the dotted line position shown in said figure for raising and holding the switch blade 15 out of engagement with the contact 14. Upon pushing the button 36 inward shaft 31 will be rotated in 50 a reverse direction for moving the cam to the full line position shown in Figure 2.

Even though we have herein shown and described the preferred embodiment of the invention, it is to be understood that the same is 55 susceptible of further changes, modifications and improvements coming within the scope of the appended claims.

Having thus described the invention, what we claim as new is:

1. In a starter switch for internal combustion engines, a casing, a cylinder having a diametrically enlarged lower end portion fitting snugly within said casing, a piston mounted for reciprocation within said cylinder, a stem connected with the piston and operating in an opening provided in said enlarged portion of said cylinder communicating said cylinder with said casing, circuit opening and closing means arranged within said casing and controlled by the movement of said piston, an operating connection between said piston stem and said circuit opening and closing means for operating the latter, a vacuum conduit connected with the upper end of said cylinder to cause the upward movement of 75

said piston, a slide mounted on the enlarged portion of said cylinder and movable across the path of the piston stem, and interengaging means on the piston stem and said slide for holding the piston in up-position within said cylinder.

2. In a starter switch for internal combustion engines, a cylinder, a switch casing at the lower end of said cylinder, a piston mounted for reciprocation within said cylinder, a switch in said casing, a rod for said piston movable into and out of said switch casing, an operating connection between said piston rod and said switch for operating the switch, a vacuum line connected with the top of said cylinder to hold the piston in position for normally retaining the switch in open condition, a slide mounted in the lower end of said cylinder, inter-engaging means on the piston rod and said slide cooperable when the slide is in one position for holding the piston in position to retain the switch in open condition, an accelerator pedal and an operating connection between said accelerator pedal and said slide for transmitting movement of the pedal to said slide.

25. 3. In a starter switch for internal combustion engines, a casing, a cylinder having a diametrically enlarged lower end portion fitting snugly within said casing, a piston mounted for reciprocation within said cylinder, a stem connected 30 with the piston and operating in an opening provided in said enlarged portion of said cylinder communicating said cylinder with said casing, circuit opening and closing means arranged within said casing and controlled by the movement of said piston, an operating connection between said piston stem and said circuit opening and closing means for operating the latter, a vacuum conduit connected with the upper end

of said cylinder to cause the upward movement of said piston, a slide mounted on the enlarged portion of said cylinder and movable across the path of the piston stem, and interengaging means on the piston stem and said slide for holding the piston in up-position within said cylinder, 5 said circuit opening and closing means including a fixed contact, a spring contact, and remote control cylindrical means for moving the spring contact out of engagement with the fixed contact 10 and to retain the spring contact in said position relative to the fixed contact independently of the piston.

4. In a starter switch for internal combustion engines, in combination, a circuit opening and 15 closing device, including a fixed contact, a spring contact anchored at one end, a piston, a cylinder, said piston mounted for reciprocation in said cylinder, a rod connected with said piston, an operating connection between said rod and said 20 spring contact, said contact adapted to move the piston toward one end of said cylinder, and the operating connection between said piston rod and said spring contact being operable to transmit 25 movement of the piston to the spring contact only upon movement of the piston in a reverse direction toward the opposite end of said cylinder, for moving the spring contact out of engagement with the fixed contact, an accelerator pedal, means operatively connected with the accelerator 30 pedal adapted to engage the piston rod for holding the piston in circuit opening position, and mechanical means for moving the spring contact out of engagement with the fixed contact and relative to the piston rod. 35

EDWIN L. MCKINNEY.
HAROLD E. EAGLE.
